UNITED STATES PATENT OFFICE.

NATHAN HATCH, OF ALBANY, NEW YORK.

COMBINATION GARMENT.

Application filed June 12, 1923. Serial No. 644,835.

To all whom it may concern:

Be it known that I, NATHAN HATCH, a citizen of the United States, and a resident of Albany, county of Albany, State of New York, have invented certain new and useful Improvements in Combination Garments, of which the following is a specification.

This invention relates to an article of wearing apparel and specifically to a combination garment for men, women and children.

The garment is particularly adapted for underwear, such as union suits, but is not necessarily confined to such uses because the invention is obviously applicable to other types of union or combination garments, such as athletic suits, pajamas and overalls.

In the interest of brevity the following description particularly pertains to union or combination garments for underwear, but as stated above, it is obvious that the same construction may be utilized in making the other garments above mentioned.

One of the objects of the invention is to provide a garment of the union or combination type in which it is not necessary to provide buttoning or fastening means ordinarily required to close the chest or back portions in garments of this type.

Another object of the invention is to provide a garment of the union or combination type which is, for the most part, constructed of non-elastic fabric, such as nainsook or other non-elastic fabric suitable for the particular purpose for which the garment is to be used, so that such a garment may be easily donned or taken off, and which will nicely fit the body of the wearer without the use of buttons or fastening means.

A still further object of the invention is to provide a garment of the type described in which the chest and back portions only, or the shoulder, chest and back portions are provided with inserts of elastic fabric, preferably of knitted webbing, so constructed that the shoulder portions may be displaced laterally to permit the garment to be readily donned or removed by stepping into it through the neck opening, yet when worn, the chest, shoulder and back portions are positioned to adequately cover and nicely fit the body of the wearer.

With these and other objects in view the invention comprises the garment described and illustrated in the accompanying specifica-

cation and drawings and defined in the claims.

The various features of the invention are illustrated in the accompanying drawings in which:

Fig. 1 is an elevation showing the front of a garment embodying my invention.

Fig. 2 is a similar view showing the back of said garment.

Fig. 3 is a fragmentary view in perspective, partly broken away and partly in section on line 3 of Fig. 1.

Fig. 4 is a view of the upper portion of the garment, the neck opening being stretched in order to don the garment by stepping into it; in this figure the stretched neck opening is bounded by the full lines and the dotted lines show the portions of the garment in place on the body of the wearer when donned.

Figs. 5, 6, 7 and 8 are views similar respectively to Figs. 1, 2, 3 and 4 of a modified construction of garment.

Referring more particularly to the accompanying drawings, the front chest portions are designated 10 and 11, the back portions 12 and 13, the shoulder portions 25 and 26, the central body portions 14 and 15 and the leg portions 16 and 17. All of these portions are constructed of woven non-elastic fabric, such as nainsook, or other suitable woven non-elastic fabric when used for underwear. Between the back body portions 15 and the back portions 12 and 13 may preferably be inserted a horizontal strip of elastic knitted webbing 18, in order to stretch and give when the wearer bends over, and therefore relieve the strains thus brought upon that portion of the garment.

The particular structure involving my improvements consists in the placement in the upper trunk portion of the garment of longitudinally disposed gussets or inserts 20 and 30, preferably triangular in shape, of elastic knitted webbing, the insert 20 being placed in the front portion of the garment between the chest non-elastic portions 10 and 11, and insert 30 being placed in the back portion of the garment between the back-non-elastic portions 12 and 13, both of the elastic knitted webbing inserts extending upwardly from the points substantially at the waist line of the garment, so as to fill the triangular shaped openings which have been respectively formed between the chest portions 10 and 11, and the back portions

12 and 13. As shown, the back elastic insert preferably extends a greater distance upwardly than the front insert. Thus, the neck opening O is formed between the inner 5 side edges 40 and 42 of the front and back portions 10 and 12, and 41 and 43 of the front and back portions 11 and 13, and the upper edges 22 and 32 of the elastic portions 20 and 30.

10 It has been found desirable in the construction of garments for wear by persons of large frame and considerable waist measurement, to provide elastic knitted webbing shoulder pieces 52 and 54, as shown, which 15 are secured respectively to the upper ends of the front and back portions 10 and 12 and 11 and 13. The garment is thus stretched so that the opening O is made larger than when the shoulder pieces 25 and 26 are made 20 of non-elastic material. This structure permits the garment to be readily donned or taken off the body when the wearer is of heavy frame or has a large waist measurement. The elasticity of the shoulder pieces 25 causes the garment to assume its proper shape and nicely fit the body when donned.

As clearly shown in Figs. 4 and 8, the garment may be donned or taken off the body of the wearer by stretching the shoulder portions 25 and 26 or 55 and 56, as the case may be, outwardly in the direction of the arrows therein shown, thus stretching the upper or base portions 22 and 32 of the elastic knitted web inserts 20 and 30 so as 35 to extend the neck opening O into a body opening which may be drawn up over the body of the wearer when the garment has been stepped into in the usual manner of donning a union or combination garment.

40 Conversely, the same stretching of the neck opening of the garment is effected in order to remove it from the body of the wearer.

The garment may be finished in the usual way with the ribbed edges and the arm, leg 45 and neck portions being provided with the usual border. The garment may also be provided with the fly and overlapping seat portions common to union suits.

As changes of construction could be made 50 within the scope of my invention it is intended that all matter contained in the above description or shown in the accompanying drawings shall be interpreted as illustrative and not in a limiting sense.

55 Having thus described my invention what I claim as new and desire to secure by Letters Patent is:

1. A bifurcated garment constructed largely of substantially non-elastic fabric 60 which fabric extends around the sides and under the arms thereof, said garment being provided with shoulder straps and with a longitudinally disposed relatively small insert in the upper portion thereof, positioned 65 between the loops or arm holes formed by

the shoulder straps of opposite shoulders, the said insert being of a fabric of greater elasticity than that of the main fabric of the garment which when stretched permits the shoulder portions to be displaced to 70 enable the body of the wearer to pass therebetween as the garment is donned or doffed and upon being released when donned draws the shoulder portions and straps to their proper positions and closes the garment 75 snugly about the neck.

2. A bifurcated garment, the trunk portion of which is constructed largely of substantially non-elastic fabric, said non-elastic fabric extending around the sides and under 80 the arms, the said garment being provided with elastic shoulder straps and centrally disposed relatively small elastic inserts in the chest and in the back portions thereof intermediate of the shoulder straps, each 85 insert extending downwardly from the neck opening and so situated as to permit the neck opening to be enlarged and also to hold the neck opening to its normal size.

3. A combination bifurcated garment, the 90 upper or trunk portion of which is constructed largely and the leg portion of which is constructed wholly of substantially non-elastic fabric, said garment being provided with shoulder strap members at its 95 upper end and longitudinally disposed relatively small inserts of a fabric having greater elasticity than that of the first mentioned fabric, the said inserts being placed in the chest and in the back portions of the 100 garment between said shoulder straps and extending downwardly from the neck opening, and stretchable to permit the insertion of the body between said shoulder straps when donning or doffing the garment and by their 105 elasticity to resume their normal positions to draw the shoulder straps and upper portion of the garment towards the neck when the garment is donned.

4. A combination bifurcated garment, the 110 upper or trunk portion of which is constructed largely and the leg portion of which is constructed wholly of substantially non-elastic fabric, said garment being provided with elastic shoulder strap members at its 115 upper end, and longitudinally disposed relatively small elastic inserts in the chest and in the back portions thereof between said shoulder straps, and extending downwardly from the neck opening, said shoulder straps and said inserts being stretchable to permit the insertion of the body of the wearer between said shoulder straps when donning or doffing the garment, and by their elasticity 120 to resume their normal positions upon the body of the wearer when the garment is doffed.

5. A combination bifurcated garment the upper or trunk portion of which is constructed largely and the leg portion of which 125

is constructed wholly of a fabric of uniform texture of substantially negligible elasticity, said garment being provided with elastic shoulder strap members at its upper end and with longitudinally disposed relatively small inserts of a fabric having greater elasticity than that of the first mentioned fabric, the said inserts being placed in the chest and back portions of the garment between the loops or arm holes formed by the shoulder straps of opposite shoulders and extending downwardly from the neck opening and stretchable to laterally displace the shoulder straps to permit the insertion of the body between said shoulder straps when donning or doffing the garment, and by their elasticity to resume their normal positions to draw the shoulder straps snugly upon the shoulders and the upper portion of the garment towards the neck when the garment is donned.

NATHAN HATCH.
